UNITED STATES PATENT OFFICE

EDWARD S. BRADFORD, JR., OF LONGMEADOW, MASSACHUSETTS, ASSIGNOR, BY DIRECT AND MESNE ASSIGNMENTS, OF ONE-HALF TO SPRINGFIELD WIRE & TINSEL CO., OF SPRINGFIELD, MASSACHUSETTS, A CORPORATION OF MASSACHUSETTS, AND ONE-HALF TO METAL TEXTILE CORPORATION, OF ORANGE, NEW JERSEY, A CORPORATION OF DELAWARE

SCOURING UTENSIL

Application filed August 11, 1930. Serial No. 474,551.

This invention relates to an improved scouring utensil of gimped metallic strand material and to a method of making such a utensil.

5 The material by itself is old and widely used in various forms, usually with a textile thread to carry the twisted metallic filament and this is used both in woven and unwoven form. The problem of this invention is to make an 10 improved and fluffy arrangement of a mass of such material for scouring purposes. In addition, it is desirable to avoid all possible hard spots of any substantial bulk in the arrangement. Of course it is desirable to build 15 such a utensil at a low cost and with a saving of useful material.

These several objects are accomplished by the particular method and structure which I will disclose in detail. The invention in its 20 various aspects is best understood from the detailed description of the method discovered to make a preferred embodiment.

In the drawing—

25 Fig. 1 is a view of the twisted metallic strand as used in its preferred form;

Fig. 2 is a skeleton view of a support on which a skein of the strand has been wound;

30 Fig. 3 is a skeleton view of the skein on the support, after tying and before it is released from its skein-winding position; and

Fig. 4 is a view of my new scouring utensil formed by releasing the skein, after it has been tied to hold the strands.

To accomplish the invention I wind a skein 35 of a strand 5 like that in Fig. 1 on a suitable support 7, as in Fig. 2. The winding is done under usual tension.

The twisted metal filament or strand 5 is 40 somewhat like a weak coil spring. And the winding tension in making the skein results in somewhat the same action as putting a strand of a weak coiled spring into skein form. I make particular use of these characteristics as will be pointed out.

45 When the skein is formed and while it is under the winding tension I hook a binding cord or wire 9 through the loop of the skein at one end and pull this binding wire up into the very end of the loop and then pass the 50 wire around the skein body in a plane paral-

lel to the length of the skein at the end bend. Then I tightly tie or bind the strands of the skein as shown in Fig. 3. The other end of the skein is tied down in the same way.

With the strands tied down at each end of the skein in this simple fashion, they are taken off the skein support 7. Immediately the slightly tensioned strands relax, the tied points 9 of the skein approach each other, the outside strands of the skein are crowded by the inside ones into bowed form between the tied points 9, as shown in Fig. 4. This bowed form of the strands indicated in Fig. 4 gives the general direction of the strand portions between points 9. In addition there is a tendency for each portion to back twist or tangle with the result that there are a multitude of short curls throughout the ball mass. These curls are more pronounced and occur in greater number inside the mass than on the outside.

70 The action is much the same as if the skein were made with loops from a very long coil spring. The strand portions between points 9 are bowed out and arrange themselves in a ball-like formation and as if the points 9 were the opposite poles of a globe.

75 This ball of metallic gimped cord or strands is sufficiently tangled for the strands to work together in scouring. They are all tied together on the outside of the ball which leaves the inside soft, movable, and loose for holding water like a sponge. And more important, the interior of the ball in its loose state can be washed out to clean the utensil 80 itself. Where the strands of such a ball are massed by tying them at the center or core, there is a hard mass which acts as a trap for grease and dirt. I avoid this by tying my strands on the outside of the ball and leaving the inside free. This is only one of the detailed advantages in the new form of utensil.

85 Another is in the fact that the strands are in the best coordinated position for scouring—that is, with their length extending between the opposite poles of the ball and bowed outwardly toward the surface where the work must be done. This gives an improved efficiency to the utensil.

The advantages mentioned are only some of many that can be listed upon a full analytical consideration of the new utensil.

It may be desirable to wind the skein over 5 a piece of soap, sponge, or other center piece, which will be surrounded by the gimped strands in the ball. The latter will be pushed into a bigger ball for a given weight of gimped strands than can be formed without 10 a center piece. My arrangement is particularly adapted to such a central addition to the utensil.

It may be desirable in some instances to 15 turn the skein inside out, preferably on its support, before releasing it from its winding tension. This action will put the longer outside loops of the strands on the inside of the ball and the shorter ones on the outside. It will tend to crowd the material between 20 points 9 so that the ball will be a little harder with the strands on the outside of the ball drawn down a little tighter than in the arrangement first described.

I am aware that there are prior scouring 25 utensils made of metallic gimped cord and in various forms. My claims are directed to the new utensil as a hand device and to the improved method of making such a utensil.

I do not desire to limit or restrict the invention as claimed except as the same may be 30 legally necessary by the condition of the prior art.

What I claim is:

1. A cleaning utensil of the class described 35 comprising two ring binding elements, a mass of metallic gimped strand material formed into loops, each loop passing once through each binding element at substantially opposite points of the loop, there being 40 enough of said loops to form a loose substantially spherical mass between the binding elements, said loops being tied only by said binding elements.

2. A strand of abrasive metallic material 45 looped upon itself to provide a multiplicity of elongated looped sections, means gathering and securing the loop ends of each side in converging relation, whereby each of said sections is positioned one adjacent the other 50 and disposed radially about an axis extending between its opposite gathered loop ends and lies in a plane radiating from a central axis intersecting the gathered ends to form a substantially spherical resilient body.

55 In testimony whereof I have affixed my signature.

EDWARD S. BRADFORD, JR.
